UNITED STATES PATENT OFFICE.

HARRY J. BOSWORTH, OF CHICAGO, ILLINOIS.

ELECTRIC-LAMP SUPPORT.

1,246,533.

Specification of Letters Patent. Patented Nov. 13, 1917.

Application filed April 26, 1917. Serial No. 164,826.

To all whom it may concern:

Be it known that I, HARRY J. BOSWORTH, a citizen of the United States, residing at Chicago, in the county of Cook and State of Illinois, have invented a certain new and useful Improvement in Electric-Lamp Supports, of which the following is a full, clear, concise, and exact description, reference being had to the accompanying drawings, 10 forming a part of this specification.

The present invention relates broadly to illumination and more particularly to light supports.

An object of my invention is to provide 15 a light support which is strong and durable, simple in construction, capable of movement through a horizontal plane and adapted for quick and easy installation.

My invention contemplates particularly 20 the provision of suitable supporting means for the lamp carrying element whereby an electric conductor or conductors may be carried in the support without danger of becoming injured when the support is adjusted in various positions.

Other objects of my invention not hereinbefore pointed out will appear from the following detailed description and the claims, taken with an inspection of the accompanying 30 drawings, in which—

Figure 1 is a perspective view of a light support embodying the improvements of my invention;

Fig. 2 is an enlarged vertical sectional view of the supporting bracket and lamp carrying member; and

Fig. 3 is a transverse sectional view of the same.

Referring more particularly to the drawings, wherein similar characters of reference designate like and corresponding parts throughout the various views, 10 designates the supporting bracket which consists of a channel portion 11 having end walls 12 provided with concentric openings 13. Feet 14 and 15 are cast integrally with the free ends of the channel portion of the bracket, said feet being provided with suitable openings through which fastening screws may pass 50 to engage with a window frame, wall or any vertical partition or the like.

The lamp carrying element in the present instance includes a U-shaped conduit section 16, one free end of one leg of the conduit section being reduced and designated 17, the 55 reduced portion affording a shoulder 18 which is adapted to engage the upper end wall of the bracket member when the reduced portion is inserted into the opening 13 as best shown in Fig. 2. The free arm of the 60 U-shaped conduit section carries a lamp 19 of any standard design, preferably electric and of the type employing the indirect lighting principle. However, the structure and 65 the type of lamp employed are not material.

The reduced portion of the conduit section is open on its lower end to receive an electrical cable or conductor 20 preferably of the flexible type which is adapted to supply current to the lamp 19. The interior of 70 the conduit may be lined with insulation 21.

In use it will be apparent that swinging the lamp on the bracket 11 as a bearing, the rays of the lamp may be directed to any point throughout a given arc of a circle, 75 the device being particularly adapted for use in connection with dental work or wherever a movable lamp is required. The supply of current to the lamp may be controlled at the lamp or from a distant point, as desired, 80 and it will be apparent that owing to the manner in which the conductor and the conduit are aligned in the bearing, there is no danger of twisting the conductor and thus 85 subjecting the same to undue wear, which might result in short circuit or otherwise disabling the lamp.

While I have shown and described the device as embodying a specific structure I reserve the right to make such changes there-in as do not depart from the spirit and scope 90 of the invention as claimed.

I claim:

1. In combination a bracket composed of a channel section having end walls and lugs 95 to support the same, said end walls having concentric openings therein, a lamp support composed of an interiorly insulated conduit section having a lamp on one end and the opposite end reduced for reception in said 100 opening, said reduced portion forming a shoulder to rest upon the upper end of the

bracket, and a flexible conductor disposed in said conduit concentric therewith and extending from the open end thereof.

2. In combination, a channel bracket having end walls and concentric openings in said end walls, a conduit section having a lamp on one end and the opposite end open and reduced to form a shoulder, said reduced

end being adapted for reception in the openings in said channel and said shoulder supporting the conduit section in said openings, and a conductor in said conduit disposed through said open end. 10

In witness whereof, I hereunto subscribe my name this 24th day of April, A. D. 1917. 15
HARRY J. BOSWORTH.

Copies of this patent may be obtained for five cents each, by addressing the "Commissioner of Patents, Washington, D. C."
